GAME APPARATUS

Bruno Radtke, Chicago, Ill., assignor to John F. Meyer, Chicago, Ill.

Application August 24, 1934, Serial No. 741,202

2 Claims. (Cl. 194—1)

This invention relates to a game apparatus.

It is an object of this invention to provide an improved game apparatus which is relatively simple and inexpensive in construction and efficient in use.

A further object of this invention is to provide in a game apparatus which includes an inclined playing board, means for elevating the balls from a point below the playing board onto the same, and means including a new and improved arrangement of inclined runways for returning balls which pass through the exit openings in the playing surface back to the elevating means in such a manner that the balls do not become jammed or piled upon each other at the point where they enter the elevating means, as frequently happens in the use of prior art game apparatus.

A further object of the invention is to provide in a game apparatus, a novel device for preventing fraudulent operation of the game apparatus, or, what is commonly known in the trade as "milking" the apparatus; said device including the elevating means, a coin slide, and means coacting with the elevating means and coin slide to prevent fraudulent operation of the elevating device after a predetermined number of operations thereof, when the coin slide is moved from its initial or coin-receiving position toward coin-discharging position.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a fragmentary top plan view of a game apparatus embodying a preferred form of the invention;

Fig. 2 is a vertical sectional view on line 2—2 of Fig. 1; and

Fig. 3 is a fragmentary sectional detailed view on line 3—3 in Fig. 1.

A game apparatus embodying a preferred form of the invention is generally indicated at 10 in the drawing, and comprises a cabinet 11 which includes an inclined playing board 12; the inclined playing board 12 being provided with ball exit openings 13 and 14; and there being arranged below the inclined playing board 12 a sliding panel or board 15 which is provided with ball exit openings 16 which are adapted to be registered with the ball exit openings 13 by slidable movement of the board 15.

In carrying out the present invention, there are provided below the slidable board or panel 15 oppositely inclined ball return runways 17 and 18 which converge toward each other from opposite ends of the playing board 12 and merge into a runway 19; the runway 19 extending transversely of the inclined playing board 12 below the latter and being inclined toward that side of the cabinet 11 at which is arranged the ball elevating device, generally indicated at 20. The transverse runway 19 communicates with an inclined runway 21 which is inclined toward the elevating device 20, and the spent playing balls 22 are fed one at a time from the ball return runway 21 into a vertical guideway 23 through which they are elevated up to the level of the playing surface 12 by means of a segmental elevating member or quadrant 24; the elevator 24 having a ball seat portion 25 which works in the guideway 23.

The elevating member 24 is pivotally mounted in the cabinet 11, as at 26, Fig. 2, and has a laterally extending arm 27 which is engageable with the end portion 28 of a latch member 29; the end portion 28 of the latch member 29 being projected through, and being slidable in, a slot 30 which is formed in a plate 31; the plate 31 being stationarily mounted in the cabinet 11 upon the upright supporting wall 32 therein, as shown in Fig. 2.

At its opposite end the latch member 29 has an upwardly extending portion 33 which is pivotally connected to an arm 34 of a latch operating member 35; the member 35 being pivotally mounted in the cabinet 11 as at 36 and having an arm 37 which projects laterally and horizontally over the coin slide 38; and the coin slide 38 is provided with an upwardly extending pin or lug 39 which is arranged in the path of movement of the arm 37 of the latch operating member 35.

The game apparatus 10, as shown, includes a conventional ball propelling device or plunger 40 and the segmental elevator 24 is operated by means of a slide rod 41 in a conventional manner.

Operation

In the operation of the new apparatus, the balls are propelled one at a time by the propelling device 40 up onto the inclined playing surface 12 and gravitate thereover so that they may enter into the ball exit openings 13 or into the exit opening 14; the balls being normally retained in the exit openings 13 and 14 by means of the slid-

ing panel 15, but are discharged therefrom by inward movement of the sliding panel 15, which may be accomplished by operation of the coin slide 38; the inner end of the coin slide 38 engaging an abutment member 43 which is carried by the slide board 15 at the lower end of the latter.

As the balls are discharged from the exit openings 13 and 14 they fall, respectively onto the inclined runways 17 and 18 and roll down the latter into the transverse runway 19; and they pass from the runway 19 into the runway 21 from which they are fed, one at a time, into the guideway 23 wherein they are elevated one at a time up to the level of the playing surface 12 by means of the elevator 24 and its ball seat portion 25.

By means of the foregoing arrangement of ball return runways, the balls are prevented from piling up or jamming at the point where they are fed into the elevator guideway 23, and thus an objectionable feature of the prior art apparatus is eliminated.

When the elevator operating slide rod 41 is pushed inwardly to operate the elevator 24 the laterally extending arm 27 of the elevator 24 engages the end portion 28 of the elevator latching member 29 and moves the end portion 28 of the said latch member 29 in the slot 30 which is provided in the plate 31; the latch member 29 being moved from full to dotted line position, as shown in Figs. 1 and 2; and as the latch member 29 is thus moved from full to dotted line position, Figs. 1 and 2, by engagement of the arm 27 of the elevator 24, the said elevator arm 27 passes out of engagement with, and moves above, the end portion 28 of the elevator latch member 29, whereupon the resetting spring 42 for the elevator latching member 29 retracts the latch member 29 back to its initial or full line position, as shown in Fig. 2, and in this position of the latch member 29, the end portion 28 thereof is disposed in the right hand end portion of the slot 30 (Fig. 2). In this position of the latch member 29, the end portion 28 thereof is disposed in the path of the elevator arm 27 which falls, by gravity, back onto the end portion 28 of the latch member 29, thereby urging the said end portion 28 against the action of the spring 42, into the notch which provides a seat for the end portion 28 of the latch member 29 so that the elevator 24 cannot be returned to its initial or ball receiving position until the end portion 28 of the latch member 29 is again moved back to normal or ineffective, position (Figs. 1 and 2), which can be accomplished only by retracting the coin slide 38 which acts through the lug 39 and member 37—35—34 to move the end portion 28 of the latch rod 29 from right to left (Fig. 1); hence if a player attempts to operate the game apparatus fraudulently, or, as it is called in the trade, to "milk" the machine by holding in the coin slide 38 and operating the elevator 41—24, he will be able to accomplish only one operation of the elevating device 41—24, since when the coin slide 38 is moved from coin-receiving toward coin-discharging position, (as in Fig. 1) the upright lug or pin 39 which is carried by the coin slide 38 is moved away from the arm 37 of the latch

operating member 35, whereupon the spring 42 operates upon the latch member 29 to pull the end portion 28 thereof back into position (as in full lines, Fig. 1) to engage the elevator arm 27 and thereby prevent further operation of the elevator 24 and its operating rod 41.

However, as the coin slide 38 is moved back toward, or into, coin-receiving position the upright pin or lug 39 which is carried by the coin slide 38, engages the arm 37 of the latch-operating member 35 and thereby pivots the latter and the latch member 29 (from dotted to full line position, counter-clockwise, Fig. 1), thereby moving the end portion 28 of the latch member 29 (from dotted to full line position, Fig. 1) in the slot 30; thus moving the said end portion 28 of the latch member 29 out of latching engagement with the arm 27 of the elevator 24 and thereby freeing the elevator 24 and its operating slide rod 41 for further operation.

When the coin slide 38 is again pushed in, toward coin-discharging position, the upright pin or lug 39 carried thereby is moved away from the arm 37 of the latch operating member 35 whereupon the spring 42 acts upon the latch member 29 to project the end portion 28 thereof back into latching engagement with the arm 27 of the elevator 24 (from full to dotted line position, Fig. 1).

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a game apparatus which includes a cabinet and a member within the cabinet providing a ball playing surface; means for elevating balls onto the said playing surface; a coin-controlled member; and means coacting with said controlled member for latching said elevating means against further operation after one operation thereof when said coin-controlled member is moved from its initial or coin-receiving position.

2. In a game apparatus which includes a cabinet and a member within the cabinet providing a ball playing surface; means for elevating balls onto the said playing surface; a coin-controlled member; means coacting with the said coin-controlled member to prevent further operation of the said elevating means after one operation thereof when the said coin-controlled member is moved from its initial or coin-receiving position; and means coacting with said coin-controlled member to release said latching means from latching engagement with said elevating means when said coin-controlled member is returned to its initial or coin-receiving position.
